UNITED STATES PATENT OFFICE

THEODORE HENRY KRUEGER, OF NEW YORK, N. Y., ASSIGNOR TO BETTER PACKAGES, INCORPORATED, OF SHELTON, CONNECTICUT, A CORPORATION OF NEW YORK

ADHESIVE TAPE FOR FASTENING PACKAGES AND FOR LIKE PURPOSES

Original application filed May 2, 1930, Serial No. 449,152, and in Great Britain October 31, 1930.
Divided and this application filed August 7, 1930. Serial No. 473,747.

This invention relates to adhesive tape for fastening packages and for like purposes, and has for its object to provide an improved form of such tape which will enable an operator manually to remove from the apparatus a strip of adhesive tape which has been, at least partially, moistened, without the risk of soiling his fingers by contact with the moistened gum on the strip, and without causing moistened gummed surfaces of the tape to adhere to one another, and a further object is to enable the operator accurately and quickly to place the tape on the package to be sealed (especially in a case where it is desired that the longitudinal centre line of the tape should coincide with the "seam" of the package to be sealed).

According to this invention the improved tape is divided longitudinally into three zones (i. e. a central zone and two lateral zones or flanges) by parallel lines of weakness along which said tape as a whole will bend readily to a channelled cross-section with the gum inwards, so that the flanges at the sides may be gripped by the fingers of the operator without touching the moistened gum. The lines of weakness may be formed by an initial or preliminary creasing, scoring or other suitable weakening of the tape itself before the gum or the like is applied thereto, or by creasing or bending the tape after the gum has been applied thereto, thus causing the dried gum to crack along predetermined lines, or the gum may be scored or scratched along such lines.

The distance between the lines of weakness depends, to some extent, upon the average size of an operator's finger tip, and, to some extent, upon the width of the tape itself, and should be at least one eighth of the width of the strip, and not less than one quarter of an inch (whichever is the greater), and not more than seven eighths of said width or 8½ inches (whichever is the less).

The improved tape of this invention is made up in rolls as is usual with tape for fastening packages and it may be used in any known machine, but preferably in the machine forming the subject of application for Letters Patent Serial No. 449,152, filed May

2, 1930, by which it may be caused to assume and retain the desired cross-section.

In the accompanying diagrammatic drawing Figure 1 is a cross-section of a piece of creased tape, Figure 2 is a perspective view 55 showing a piece of tape as gripped by an operator, and Fig. 3 shows a form of tape which is previously scored or otherwise weakened along the crease lines.

For convenience of operation the tape 60 should be fed through the apparatus so that the gummed surface is presented downwards. When so fed through an ordinary machine, the tape may be delivered flat, or when fed through a machine such as that forming the 65 subject of application for Letters Patent Serial No. 449,152, filed May 2, 1930, it may be delivered with a cross-section as shown in Figure 1, and the act of gripping the tape 70 lightly from above by the thumb and the second finger of the operator tends to bend the tape about the lines of weakness, as shown in Figure 2, and to force down the marginal zones or flanges *a a* of the tape, whilst the 75 first or index finger of the operator will bear naturally on the central zone *b* (the web of the channelled section) and prevent said central zone from assuming such curvature as would enable the marginal flanges to touch 80 and adhere to one another. It is desirable that the initial pressure of the first or index finger of the operator on the central zone *b* should be such as to cause a slight concavity 85 of the outer or upper (ungummed) surface thereof as in that event the grip of the thumb and second finger of the operator being substantially in the plane of said central zone, tends to cause the latter to retain such curvature (and hence prevent the marginal zones 90 or flanges *a a* from touching and adhering) until the tape is applied to the package or the like.

In Figure 3, I have shown tape *X'* which prior to the introduction into the machine is scored or otherwise weakened along two 95 parallel lines *p* and *q* in order to facilitate bending of the tape along these lines into channelled shape. This tape may be wound in a roll and used in the machine shown or 100 in machines of different type.

This invention is confined to manually applied tape, in contradistinction to tape having a single central crease which has been formed in a machine for the purpose of applying, mechanically, a strip of measured moistened and severed tape directly to the corner of a paper or like box.

This application is a division of my co-pending application Serial No. 449,152, filed

10 May 2, 1930.

I claim:—

1. Adhesive tape for fastening packages and for like purposes, divided longitudinally into three zones by parallel lines of weakness 15 along which said tape as a whole will bend readily to a channelled cross-section with the gum inwards, so that the flanges at the sides may be gripped by the operator without touching the moistened gum, and wherein the 20 distance between the lines of weakness is at least one eighth of the width of the strip, and not less than one quarter of an inch (whichever is the greater), and not more than seven eighths of said width or three and one-half 25 inches (whichever is the less).

2. Adhesive tape for fastening packages and for like purposes bent longitudinally into channel shape of fixed dimensions with the 30 gummed surface inwards, such shape being fixed by two crease lines only forming the edges of the sides of the channel, the spacing of said crease lines being such as to permit the sides of the tape to be gripped by the 35 fingers of the operator without touching the moistened gum and to be applied with the gummed sides to the work.

3. Adhesive tape for fastening packages and for like purposes bent longitudinally into channel shape of fixed dimensions with the 40 gummed surface inwards, such shape being fixed by two crease lines only forming the edges of the sides of the channel, the spacing of the crease lines being such as to permit the sides of the tape to be gripped by the 45 fingers of the operator without touching the moistened gum, the width of the outer zones being sufficiently narrow so that pressure on the middle zone is effective to avoid contact of the two outer edges of the tape.

50 4. Adhesive tape for fastening packages and for like purposes divided by two longitudinal lines of weakness to enable the tape to assume a channel shape, having a pair of side portions engageable by the fingers of the 55 operator without touching the moistened gum, and a central unweakened portion of a width sufficient to receive a further finger of the operator.

60 THEODORE HENRY KRUEGER.
